UNITED STATES PATENT OFFICE.

SAMUEL M. SAMTER AND CLARENCE L. COBE, OF SAN FRANCISCO, CALIFORNIA.

OPERA CHAIR.

1,411,747.

Specification of Letters Patent.

Patented Apr. 4, 1922.

Application filed August 18, 1920. Serial No. 404,408.

To all whom it may concern:

Be it known that we, SAMUEL M. SAMTER and CLARENCE L. COBE, citizens of the United States, and residents of the city and county of San Francisco, California, have invented a certain new and useful Opera Chair, of which the following is a specification.

This invention relates to chairs and more particularly to opera chairs.

It is one of the objects of the present invention to provide an improved opera chair with relatively movable seat and frame parts to facilitate access to and egress from chairs in aisles or rows.

A further object of the present invention is to provide an improved opera chair involving a rigid, substantial and stationary leg frame structure and a seat, with a back, movable to and fro on the leg frame between predetermined limits.

It is a further object of the invention to provide means for facilitating this to and fro movement, as occasion requires, on the frame structure, and further to provide an improved anti-friction bearing between the seat and the frame structure.

Another object of the invention is to provide a novel opera chair of few and simple parts that are of an inexpensive character.

The invention possesses other objects and features of advantage, some of which, with the foregoing, will be made manifest in the following description of the preferred form of the invention which is illustrated in the drawings accompanying and forming part of the specification. It is to be understood that it is not intended to limit the invention to the embodiment shown by the said drawings and description, as variations may be adopted within the scope of the invention as set forth in the claim.

In the drawings, Figure 1 is a perspective of the improved chair with the seat in its forward position.

Figure 2 is a vertical section through the seat structure and between the legs of the frame on line 2—2 of Fig. 3.

Figure 3 is a cross section through the leg frames and transversely across the seat to illustrate the bearings on line 3—3 of Fig. 2.

Figure 4 is a front elevation of a portion of a row of chairs.

In the preferred embodiment, the invention comprises a leg frame structure of sub-

stantially parallel frames rigidly connected together and suitably attached to a platform, floor, or other base, and which frames are provided upon opposed faces with tracks or guides upon which operate anti-friction bearings carrying a seat that may be provided with a back; the tracks being of sufficient length to permit the chair seat to be pulled forwardly into a normal position of use and whereby, upon occasion of necessity, the seat can be pushed rearwardly, thus giving an added clearance for persons passing between the fronts and backs of rows of seats. A further feature of the invention is provision for the to and fro movement of the seat with facility, as by means of arms rigidly connected to the frames and having guided relation to members extending from the back of the chair.

A form of the invention is shown as comprising side frames of U-shaped form having downwardly extending front and rear legs 2 and 3 connected by a top bridge portion 4; the lower ends of the legs being provided, if desired, with laterally extended foot portion 5 by which the frames may be secured to the floor or platform. The front legs of a pair of frames are preferably free from any transverse connection while the rear legs are transversely connected by a suitable brace or braces 6, thus providing for rigidity of leg frame structure. Superposed at a suitable height above the leg frames are horizontally arranged arms 7—7, the front ends of which are provided with braces 8—8 extending upwardly from the tops of the leg frames.

Arranged between the bridge portions 4 of the leg frames is a seat structure preferably formed of one integral or continuous sheet of material, as metal, having a seat-forming portion 10 having an appropriate ogee surface from the front to the rear, the latter being provided with an upwardly extending back 11. The front edge of the seat 10 is provided with a downturned apron 12 that is cut away at the corners, as at 13, to provide clearance openings for a purpose to be explained.

The seat thus described is adapted to be bodily shifted from a front position, as shown in Fig. 1, rearwardly to a predetermined position; the chair seat being shown in Fig. 2 as pushed rearwardly to the back limit of movement.

This to and fro movement of the seat is

facilitated by enabling the occupant of the chair to grasp the side arms 7-7 and through arm force push the chair rearwardly or pull it forwardly while sitting on the seat and grasping the arms 7-7. The arms are shown as of tubular form to receive and guide links 15 pivotally connected at 16 to the back 11 of the seat.

The seat structure may be appropriately mounted upon the leg frames and in the present case this is accomplished by providing on the inner and opposed faces of the portions 4 of the frames, guideways or tracks having upper and lower rails 18 and 19, respectively, brought together at the front ends at 20 and at the rear ends at 21 to form closed slots for the right and left hand frames, and extending transversely between the frames, and with their ends bearing in the tracks are provided roller shafts or bars 22, arranged in parallelism, in bearings below the chair bottom 10. The chair bottom is prevented from lateral shifting movement by having guided relation between the portions 4 of the leg frames, and below the bottom of the chair seat there is provided a pair of parallel flanges or bearing portions 23, through which the roller rods or shafts 22 pass; these flanges 23 being closely contiguous to the adjacent edges of the track rails 18 and 19, and further tend to prevent lateral movement of the chair seat.

The downwardly turned apron portion of the seat bottom thus effectually conceals the transverse roller shafts 22 and their bearing members 23 and the whole chair presents an extremely practical and neat appearance, and, if desired, the seat structure may be provided with a suitable cushion or covering means not necessary to be here shown.

In Fig. 4 is shown an arrangement in which two arms 23-24 of adjacent chairs slide in one tubular arm 7; the chair frames being provided with tracks on each side. 45

What is claimed is:

An opera chair comprising rigid side leg frames, having on mutual sides closed frames forming horizontal guide channels open toward each other in vertical planes, 50 and a seat structure having downwardly extending bearing flange members running close to the inner edges of the said guide frames so that lateral movement of the seat is prevented by engagement of said flanges 55 with the frames, the flanges carrying transversely extending, parallel roller shafts, the ends of which travel in the guide-way formed by the guide frames; the forward and rearward movement of the seat structure being limited by the abutment of the rollers with the closed ends of the guideway.

In testimony whereof, we have hereunto set our hands.

SAMUEL M. SAMTER.
CLARENCE L. COBB.
